TRACK LAYOUT FOR LOADING AND UNLOADING

William E. McDonald, Salt Lake City, Utah

Application June 4, 1945, Serial No. 597,493

6 Claims. (Cl. 238-10)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates to railway car loading and unloading devices and more particularly to a device for loading and unloading refrigerator railway cars and other carriers, the floors of which, due to the use of floor gratings, do not readily lend themselves to the operation of wheeling vehicles thereover.

Considerable difficulty has been experienced in the movement of commodities into and out of railway freight cars due to the difference in height which often exists between the floor of the car and the loading dock or platform. Fork-lift trucks used to move material are subject to excessive wear and tear because it is necessary for them to negotiate a sharp incline up the conventional car plate which bridges the space between the dock and the car floor. The narrow width of most car doors adds to the difficulties which confront the fork-lift truck operator. Not only must he negotiate the sharp incline up the car plate, but he must be careful to direct the load into the car through the narrow doorway. These conditions not only make the car loading operation a time-consuming one, but also results in damage to material which frequently falls or is knocked off the lift truck.

30

An object of my invention is to provide a device which will eliminate the necessity for the fork-lift truck to enter the freight car during loading or unloading.

Another object is to provide a car loading device which will eliminate the necessity for the use of a conventional car plate.

A further object is to provide a car loading device which will make car loading and unloading a smooth, speedy and efficient operation with a minimum of stress on equipment.

Another object of this invention is to provide a car loading device which will permit loading or unloading of both ends of the car to be carried on at the same time.

45

Further objects, advantages and features will be apparent from the following specification and accompanying drawings in which:

Fig. 1 is a top plan view of the track layout comprising my invention.

50

Fig. 2 is a front elevational view of the exterior or dock stand portion of my track layout, parts being shown in section.

Fig. 3 is a fragmentary side elevational view of the structure illustrated in Fig. 2.

2

Fig. 4 is a detailed side elevational view of a swingable track connector employed in conjunction with my invention.

Fig. 5 is a detailed end elevational view showing the track connector in broken lines.

Fig. 6 is a detailed top plan view of the cross-over employed in my track layout.

Fig. 7 is a detailed section taken along lines 7-7 of Fig. 6 looking in the direction of the arrows.

Fig. 8 is a detailed sectional view taken on lines 8-8 of Fig. 6.

Fig. 9 is a fragmentary, detailed, side elevational view of the dock stand adjusting mechanism.

Fig. 10 is a front elevational view of the device shown in Fig. 9; and

Fig. 11 is a top plan view, parts being shown in section, of the device illustrated in Figs. 9 and 10.

Figure 12 is a section taken through lines 12-12 of Figure 1, showing the "dock stand" or "bridge stand" in cross-section.

Generally speaking, the car loading and unloading device of my invention comprises a portable track layout positioned on the floor of the railway car and extending out the door thereof to the dock or loading platform, terminating in a dock or bridge stand capable of vertical adjustment to compensate for the difference in height between the dock platform and the car floor.

The track layout, as shown in Fig. 1 of the accompanying drawing, comprises a pair of tracks 1 and 2 of the same gauge running parallel from dock 21, fragmentarily shown in Figure 1, to the inside of the car A (see Fig. 1). Here they diverge and track 1 runs to one end of the inside of the car and track 2 to the other inner extremity of the car. Each track consists of a plurality of sections 14 comprising a pair of inverted T-rails, the numerals 3 and 4 designating the rails of track 1, and the numerals 5 and 6 indicating the rails of track 2, and structural supports comprising diagonal braces 7 and angle-sectioned spacers 8 joined to the rails to insure the rigidity of the structure and to keep the rails at the proper gauge. The adjacent rails 3 and 6, and 4 and 5 of that portion of tracks 1 and 2 which are parallel at dock stand section 19 are rigidly joined to each other, as shown best at 13 in Figure 2, by some suitable means, for example, by welding.

The portable track layout is fabricated in unit sections 14 to facilitate its assembly and disassembly. The unit sections 14 of track are joined to each other by means of track connectors 9. These track connectors are U-shaped metal hooks

55

which swivel on pins 10 mounted on abutting spacers 8 of each unit section in such a manner that when two unit track sections are joined by inserting the pin 10 through connector holes provided in the end-most spacers 8, a rigid, portable connection is obtained under all types of moving or live loads and with adverse floor conditions.

A cross-over section 12 of the track layout enables loading or unloading operations to be carried on in opposite ends of the railway car simultaneously without the manipulation of switches or the like. The problem of retaining the double-flanged wheels B of a dolly (not shown) on the track while it transports a load of material through the cross-over 15 of the two inside rails 4 and 6 of tracks 1 and 2, respectively, is solved by the use of a cross-over plate 16 having a plurality of retainers or guides 17 disposed about the periphery thereover and parallel to the intersecting rails 4 and 6. A guide pin 18 is positioned substantially in the center of plate 16. Guide pin 18 is in alignment with the spaced free ends of rails 4 and 6 (see Fig. 6) in order that a single or double-flanged wheel of a dolly may freely pass over the cross-over section. The guiding action of the retainers 17 and the guide pin 18 prevents the dolly from "jumping" the tracks.

The cross-over section 12 is connected to the dock stand section 19 which leads to the railway car door (not shown) and bridges the space between said car door and the loading dock or platform 21. One end of the dock stand 19 is joined to the cross-over section 12 by a pair of track connectors 9 in a manner similar to the connecting means hereinbefore described in conjunction with adjacent sections 14. The other end of the section 19 is secured to supporting legs 22 which carry ratchet teeth 22'. The dock end of the dock stand section is supported on the dock 21 by a plate 23 attached to sleeves 24 slidably mounted on the legs 22. A pawl release rod 26 is mounted in the yokes 20 of the sleeves 24. A pair of pawls 25 are mounted on the pawl release rod 26 in engaging relationship with the ratchet teeth 22' on the supporting legs 22. A pair of springs 27 are positioned on the pawl release rod 26 adjacent pawls 25 to keep the pawls normally in engagement with the teeth 22'. Disengagement of the pawls 25 to permit vertical adjustment of the dock stand section is accomplished by manipulation of a handle 28 rigidly connected to rod 26. Thus the dock stand section 19 may be elevated to bring it up to the same level as the track sections inside the railway car.

That portion of the dock stand section 19 which engages the floor of the railway car may be provided with cleats 29 which grip the floor when under a load, thus preventing sliding of the dock stand section 19.

The dock stand section 19 is provided with a metal screen floor grate 30 which serves as a safe, convenient, non-skid access platform for the use of operating personnel. The under side of dock stand section 19 is provided with a suitable supporting structure comprising a plurality of leg braces 31. The ends of the tracks 1 and 2 which extend out to the dock are curved upwardly as shown at 32 in Figure 3 to prevent the wheeled carrier, such as a dolly, used to move material along the tracks, from running off the dock end thereof.

What I claim is:

1. A car loading and unloading device comprising a bridge section, one end of said bridge section being supportable by said car, ground-engaging

means supporting the other end of said bridge section, said ground-engaging means being spaced from said car, two tracks of the same gauge supported by said bridge section in parallel relation, each track comprising an inside rail and an outside rail, each of the inside rails being adjacent the outside rail of the other track, and a cross-over section supportable by said car, wherein the inside rails of said tracks intersect each other and are cut away at the point of intersection to permit the passage of a flanged wheel over said cross-over section; said two tracks leading into said car in divergent directions from said cross-over section and being supportable by said car.

15 2. A car loading and unloading device comprising a bridge section, one end of said bridge section being supportable by said car, vertically adjustable ground-engaging means supporting the other end of said bridge section, said ground-engaging means being spaced from said car, two tracks of the same gauge supported by said bridge section in parallel relation, each track comprising an inside rail and an outside rail, each of the inside rails being adjacent the outside rail of the other track, and a cross-over section supportable by said car, wherein the inside rails of said tracks intersect each other and are cut away at the point of intersection to permit the passage of a flanged wheel over said cross-over section; said two tracks leading into said car in divergent directions from said cross-over section and being supportable by said car.

20 3. A car loading and unloading device comprising a bridge section, one end of said bridge section being supportable by said car, ground-engaging means supporting the other end of said bridge section, stop means at said other end to prevent a wheel from running off said bridge section, two tracks of the same gauge supported by said bridge section in parallel relation, each track comprising an inside rail and an outside rail, each of the inside rails being adjacent the outside rail of the other track, and a cross-over section supportable by said car, wherein the inside rails of said tracks intersect each other and are cut away at the point of intersection to permit the passage of a flanged wheel over said cross-over section; said two tracks leading into said car in divergent directions from said cross-over section and being supportable by said car.

25 4. A car loading and unloading device comprising a bridge section, one end of said bridge section being supportable by said car, vertically adjustable ground-engaging means supporting the other end of said bridge section, stop means at said other end to prevent a wheel from running off said bridge section, two tracks of the same gauge supported by said bridge section in parallel relation, each track comprising an inside rail and an outside rail, each of the inside rails being adjacent the outside rail of the other track, and a cross-over section supportable by said car, wherein the inside rails of said tracks intersect each other and are cut away at the point of intersection to permit the passage of a flanged wheel over said cross-over section; said two tracks leading into said car in divergent directions from said cross-over section and being supportable by said car.

30 5. A car loading and unloading device according to claim 1, wherein said cross-over section includes a cross-over plate having a plurality of guides disposed about its periphery and a guide pin positioned substantially in the center of said cross-over plate and in alignment with the cut-

away ends of said intersecting inside rails in said cross-over section to prevent derailment of said flanged wheel.

6. A car loading and unloading device according to claim 2, wherein said cross-over section includes a cross-over plate having a plurality of guides disposed about its periphery and a guide pin positioned substantially in the center of said cross-over plate and in alignment with the cut-away ends of said intersecting inside rails in said cross-over section to prevent derailment of said flanged wheel.

WILLIAM E. McDONALD.
